(57) **CLAIM**

The ornamental design for a tent, as shown and described.

DESCRIPTION

FIG. 1 is a top plan view of a tent showing our new design;

FIG. 2 is a bottom plan view thereof;

FIG. 3 is a front elevational view thereof;

FIG. 4 is a back elevational view thereof;

FIG. 5 is a right side elevational view thereof;

FIG. 6 is a left side elevational view thereof;

FIG. 7 is a front, left side perspective view thereof; and,

FIG. 8 is a back, right side perspective view thereof.

The broken-line disclosure of elements in the views are understood to be functional aspects of the article in which the design is embodied and form no part of the claimed design.

1 Claim, 8 Drawing Sheets
